UNITED STATES PATENT OFFICE

152,215

DESIGN FOR A DISPLAY STATUETTE OR SIMILAR ARTICLE

Gordon Price, Canton, Ohio, assignor to Eaton
Manufacturing Company, Cleveland, Ohio, a corporation of Ohio

Application July 25, 1947, Serial No. 140,519

Term of patent 14 years

(Cl. D1—2)

To all whom it may concern:

Be it known that I, Gordon Price, a citizen of the United States, residing at Canton, in the county of Stark and State of Ohio, have invented a new, original, and ornamental Design for a Display Statuette or Similar Article, of which the following is a specification, reference being had to the accompanying drawing, forming part thereof.

Fig. 1 is a front perspective view of a display statuette showing my new design; and

Fig. 2 is a rear perspective view of the display statuette.

I claim:

The ornamental design for a display statuette or similar article, as shown.

GORDON PRICE.
